SEWING MACHINE

George I. Goldwyn and Nathan Waldman, Chicago, Ill., assignors to George I. Goldwyn and Herman Goldwyn, Chicago, Ill., co-partnership doing business as Goldwyn Brothers

Application January 10, 1935, Serial No. 1,135

18 Claims. (Cl. 112—162)

This invention relates to improvements in sewing machines and especially to commercial power machines which are operated at high speed and are subject to severe usage, and it consists of 5 the matters hereinafter described and more particularly pointed out in the appended claims.

In some of its phases, the invention is more particularly concerned with power sewing machines for forming an overcast or overedge stitch, 10 through cooperation between the needle, the looper and loop spreader, in the manner well known. Such a machine is well adapted for sewing in connection with relatively heavy material, such as burlap bagging.

15 When such machines as now made are used in the renovated burlap bag industry, in the production of an overcast or overedge seam, along one side and end and associated connecting corner of a turned inside out bag, they are open to 20 certain inherent objections. In such machines, the bearings for the looper and the loop spreader are disposed adjacent and beneath the throat plate. In overcasting or overedging the seam of such a bag, no matter how much care was used 25 in cleaning the bag, a certain amount of the material originally contained in the bag, and especially the dust-like particles thereof, remain in the seam. Due to rapid needle movement, which amounts to about 1600 per minute, some of said 30 dust-like particles, along with lint, are carried through the throat plate openings and will accumulate on the bearings for the rock shafts of the looper and the loop spreader.

Such dust-like particles and lint are indeed 35 destructive to said bearings and especially so when the bearings are dry with the result that they readily wear out and require expensive replacements. In attempting to overcome this objection, certain expedients have been tried. One 40 of such expedients included a force feed oiling system for said bearings. This, however, met with little success, because it was found that the oil fed to said bearing mixed with said dust particles and lint to form a pasty abrasive mass, 45 quite destructive to such bearings.

Thus in such machines, as heretofore made, the machines could be kept running and operable in a working condition only by frequent replacements and servicings which were quite expensive. This, of course, increased the cost of 50 renovating the bags.

Among the objects of the present invention, is to simplify the construction of sewing machines of this type; to drive the looper and loop spreader in a more direct manner; and to pro-

vide a machine capable of satisfactory operation at high speed with a reduced power consumption.

Another object of the invention is to provide 5 a structure for a sewing machine of this kind giving more room and greater freedom for the hands and arms of the operator with an increased safety factor and to provide a structure which will prevent dust-like particles, lint and other foreign matter from contacting the vital 10 operating parts of the machine.

A further object of the invention is to simplify 15 the mechanism for actuating the looper and the loop spreader and so to locate or arrange said mechanism as to make it run in an oil bath in an oil tight casing, which prevents dust particles and lint from the bag seams from reaching the bearings included in parts of the mechanism.

Still a further object of the invention is to provide 20 a mechanism for such a machine, where- in the arms for the rock shafts of both the looper and loop spreader are actuated by rods, in turn actuated by a forwardly and rearwardly extending crank shaft arranged to run in the oil bath.

Still another object of the invention is to pro- 25 vide a mechanism for a machine of this kind, wherein the parts are materially reduced in number and are arranged in balanced relation to run in an oil bath, so as to provide a saving not only in the initial manufacturing cost but also in 30 the power requirements for operating the same.

Again an object of the invention is to provide 35 a mechanism for a machine of this kind, which includes means for pumping oil from said oil bath to the bearings of other parts of the ma- 40 chine and which oil shall return by gravity to said bath for further recirculation to said bearings.

The above mentioned objects of the invention 45 as well as others, together with the several advantages thereof, will more fully appear as we proceed with our specification.

In the drawings—

Fig. 1 is a view partly in elevation and partly 45 in longitudinal vertical section through the operative parts of a sewing machine embodying our invention, the cover plate for the overhanging arm being omitted better to disclose the parts within said arm.

Fig. 2 is a top plan view, on a somewhat en- 50 larged scale of the bed plate and associated parts with the cloth plate, throat plate and cover plate of a certain casing on the bed plate removed better to illustrate the parts more directly involved.

Fig. 3 is a view in end elevation of the parts shown in the left hand end of Fig. 2 with the cloth plate shown in section and with a part of the needle shown better to disclose the relation 5 of the same to the looper, loop spreader and feed dog.

Fig. 4 is a detail vertical sectional view through a part of the improved sewing machine mechanism as taken on the line 4—4 of Fig. 2.

10 Fig. 5 is a transverse detail vertical sectional view through a part of the mechanism shown in Fig. 2 as taken on the line 5—5 of said Fig. 2.

15 Referring now in detail to that embodiment of the invention, illustrated in the accompanying drawings:

10 indicates, as a whole, the substantially elongated rectangular bed or base plate of the machine adapted for attachment in any suitable manner upon a support such as a bench or table 20 not shown herein. Rising from said bed or base plate is an open top casing 11 of irregular shape and of a substantial height. This casing includes a mechanism compartment 12 at one end and a combined overhanging arm supporting and 25 connecting rod eccentric receiving compartment 13 at the other end, said compartments being separated by an upright apertured wall 14 extending forwardly and rearwardly of the bed or base plate. Engaging upon that portion of the 30 casing forming the compartment 13 is the upright base portion 15 of a substantially horizontally disposed, hollow arm 16 that overhangs the longitudinal mid portion of the mechanism compartment 12. The open top of this last mentioned compartment is closed by a removable top or cloth plate 17 in a dust and oil tight manner. This plate appears in Fig. 1.

15 The mechanism compartment which as before stated is of an irregular shape, includes longitudinally extending front, rear and intermediate walls 18, 19, 20, 21 and 22 respectively. The right hand end of the walls 18 and 19 join the wall 14 by means of front and rear, transverse wall portions 23 and 24. The left hand end of 40 the wall 19 which is offset rearwardly from the wall 22, is connected to the right hand end thereof by a short wall portion 25 arranged parallel with the wall 23. The left hand ends of the walls 21—22 are connected together by a wall 45 50 26, one portion of which extends at a right angle to said walls and the other portion of which extends at less than a right angle as best appears in Fig. 2. The right hand ends of the walls 20, 21 are connected by a wall portion 27 arranged parallel with the walls 23, 24 and 25. The 55 left hand end portions of the walls 18 and 20 are connected by a rounded end wall 28. In the wall 18 is a gauge glass 29 and a drain plug 30. The walls and wall portions 20, 21 and 27 define 60 a recess 31 that is open at its left hand end and in which as will later appear, are located the looper and loop spreader of the mechanism. Rising from the base plate near the open end of the recess is an upright needle boss 32.

65 Extending longitudinally of the base plate 10 is a horizontally disposed shaft 33, which rotates continuously when the machine is in operation and constitutes the main drive shaft of the machine. This shaft is journaled at points near 70 its ends in bosses 34, 35, the former being arranged integral with the casing wall 21 and the latter being arranged in the compartment 13. Said shaft projects at its ends beyond said bosses and on the left hand end is mounted an eccentric 75 36, the purpose of which will appear later.

On the right hand end is mounted a wheel 37 (see Fig. 1) whereby power is transmitted to the shaft.

Along the rear of the base plate is located a longitudinally extending, horizontally disposed 5 rock shaft 38 that is journaled at its left hand end in a substantially L shaped boss 39 rising from the left hand end of the base plate. In said boss are top and bottom oil ducts 39a—39b that form an oil inlet and return from the interior of the chamber 12 to the bearing for the associated end of the shaft 38. In the chamber 12 and connected to the duct 39a is an oil inlet cup 39c, all as best shown in Figs. 1 and 2.

The right end of the shaft 38 is journaled 15 in a bearing boss 40 formed at the junction of the walls 19 and 25. Fixed to said shaft end within the chamber 12 is an arm 41 having a crank pin 42. This crank pin has operatively connected thereto one end of a connecting rod 20 43, the other end of which operatively engages an eccentric 44, positioned on the main drive shaft 33 near the wall 14. From the above, it is apparent that the continuous rotation of the shaft 33 in one direction is translated into a 25 rocking movement for the rock shaft 38.

To the rock shaft 38, near the boss 39 and outside of compartment 12, there are fixed longitudinally spaced, upstanding crank arms 45 carrying a crank pin 45a. Operatively engaged on 30 said crank pin is the rear end of a feed bar 46, the front end of which is made to operatively engage the eccentric 36 before mentioned. The front end of said feed bar carries a dog to project up through a suitable throat plate 35 (not shown) carried by the plate 17. It is apparent that by reason of the crank pin 45a and the eccentric 36, the feed dog will engage the material operated upon to feed the same rearwardly of the cloth plate 17 in the conventional 40 manner.

47 and 48 indicate respectively, the rock shafts for the looper and loop spreader respectively. The loop spreader rock shaft 48 is journaled in bearing sleeves 49 and 50 respectively, that are integral with the casing walls 18 and 20 near the rounded end wall 28. This shaft which is disposed substantially horizontal, extends at an acute angle to the longitudinal median plane of the feed bar and in which plane is also located the 50 needle boss 32 on the base plate.

The looper rock shaft 47 which is journaled near its ends in bearing sleeves 51 and 52 respectively, is arranged in substantially a horizontal plane and at an acute angle to the longitudinal median plane of the feed dog. The acute angle of said looper rock shaft, however, is somewhat different from that of the loop spreader rock shaft 48. For imparting rocking movement to said rock shafts 47—48 in proper timed relation, the following construction is provided:

Secured to the base plate so as to be disposed within the chamber 12, is a bracket plate 53 which includes a pair of upstanding front and rear bearing bosses 54 and 55 respectively. Journaled near its ends in said bosses is a relatively short, horizontally disposed, continuously rotating crank shaft 56. This crank shaft is disposed in a plane below and at a right angle to the main driving shaft 33 and is driven therefrom by worm gears 57 and 58 respectively. On the front and rear ends of the shaft 56, outwardly beyond the bearing bosses are secured crank discs 59 and 60 respectively. Each disc carries on one side a crank pin 61—62 respectively, each 75

disc being suitably counterbalanced on that side opposite the crank pin.

To the loop spreader rock shaft, 48, between the bearing sleeves 49 and 50, is secured an arm 63.

Operatively connecting said arm and the crank pin 61 is a pitman or connecting rod 64. This rod has ball and socket joint connections at its ends with said arm and crank pin to compensate for the relative angularity between the shafts 48 and 56. To the looper rock shaft 47 between the bearing sleeves 51 and 52 in the walls 21 and 22 is secured an arm 65. Operatively connecting said arm and the crank pin 62 is a pitman or connecting rod 66. This rod also has ball and socket joint connections at its ends with said arm and crank pin to compensate for the relative angularity between the shafts 47 and 56.

It is apparent that when the crank shaft 56 is being driven from the main drive shaft, said crank shaft through the crank discs, pins, rods and arms mentioned, will cause a rocking movement of the looper and loop spreader rock shafts 47-48.

On the rear end of the rock shaft 48 is operatively secured a loop spreader 67 and on the front end of the rock shaft 47 is secured a looper 68. If desired, a spreader loop retainer 69 may be employed on the shaft 48 in connection with the loop spreader. The looper and loop spreader just above mentioned cooperate with an associated needle later to be described, arranged axially of the boss 32 in forming the stitch which is an overcast or overedge stitch. In the formation of the stitch, the needle when descending carries its thread through the fabric or bagging to a point below the throat plate. When the needle is ascending, slack thread is formed which is forced out from the rear of the needle in the form of a loop which the looper 68 with its thread enters in passing from left to right. When the looper has reached the ends of its stroke to the right, the rocking relation between the two rock shafts 47 and 48 is so timed the spreader 67 rises and engages the thread at the front of the looper and carries it to the left of the needle. The needle on its next descent enters the loop of thread thus formed and which is then tightened in the fabric by the action of the looper as the next stitch is formed.

On the bracket plate 53 before mentioned, adjacent the gear 58, in the plane of and below the drive shaft, is an upstanding pump cylinder 70. This cylinder communicates at its bottom with a chamber 71 and opening into the top thereof are inlet and outlet valve fittings 72-73. Operatively engaged in the upstanding pump cylinder and opening at its top end therethrough is a piston or plunger 74. The bottom end of said plunger is reduced in diameter to form a stem 75 and surrounding said stem between the bottom of the piston or plunger proper and the bottom of the chamber 71 is a helical spring 76. This spring normally tends to impart an upward movement to the piston or plunger. On the main driving shaft 33 above the piston or plunger is fixed an eccentric 77 which in the rotation of the shaft engages the top end of the plunger and imparts the downward movement thereto. A thrust bearing 78 is provided on the main driving shaft between the bearing boss 34 and said eccentric 77.

By means of the eccentric and the spring 76 the piston is caused to reciprocate. On the up-stroke thereof, under the action of the spring, some of the lubricant with which the chamber 72 is substantially filled is drawn into the chamber

71 through the inlet 72. On the downstroke of the piston or plunger, lubricant is forced out of the outlet 73 for discharge to desired bearings as will soon appear.

The left hand end of the hollow overhanging arm 16 terminates in a needle bar and presser-foot bar supporting head 79, disposed substantially above the throat plate previously mentioned. The open front of said hollow arm is closed by a cover plate (not shown).

Mounted in said head for vertical reciprocation, axially in line with the needle boss is a needle bar 80. In the top and bottom of the head are bearings 81 and 82 for the needle bar.

Also mounted for vertical movement in the head, to the rear of the needle bar, is the presser-foot bar 83 carrying a presserfoot at the bottom end. 84 indicates the guide bar associated with the presserfoot bar. Removably secured to the bottom end of the needle bar 80 is a needle 85 for cooperation with the looper 68 and loop spreader 67 to form the stitch as before mentioned. Means (not shown herein) are provided whereby the presserfoot bars may be raised and lowered out of and into operative position.

Pivottally mounted in the hollow heat as at 86 is the rocking needle bar lever 87 including a relatively long load arm 88 and a power arm 89. The load arm is connected by a link and block 90 to the needle bar 80 at a point between the bearings 81 and 82. The power arm of said lever is operatively connected by a ball and socket joint 91 to the top end of a pitman or connecting rod 92. The bottom end of this pitman or rod carries a strap for operative engagement with an eccentric 93 on the drive shaft, adjacent the right hand end of the bearing. It is pointed out at this time that the bottom wall of the hollow arm 16 slopes downwardly from the bearing 82 toward the upright base portion 15 to provide a drainage 40 of lubricant from the interior of said arm, toward said base portion and back into the compartments 12 and 13.

In the top wall of the hollow arm between its ends is provided a lubricant manifold duct 94 which is connected to the outlet 73 of the pump by a tube 95.

Connected to the manifold duct 94 are tubes 96-97 and 98 respectively. The tube 96 leads to and discharges against the needle bar 80 near the top bearing 81 therefor. The tubes 97-98 lead respectively, to points to discharge upon the pivotal point 86 of the lever 87 and to the universal joint connection 91 between the load arm 88 of said lever and the top end of the connecting rod 92. The excess oil delivered to said bearings, is discharged into the hollow arm to drain back into the chamber 12 as before mentioned for reuse. In the hollow arm 16, at a point above the ball and socket joint 91 is a filler opening 99.

The machine, of course, is provided with the usual thread feed, tensioning and other devices necessary for the intended operation of the machine but as these form no part of the present invention, they are not described in detail although parts thereof appear in Fig. 1.

In operation, the compartments 12 and 13 are filled with a lubricating oil to a level above the drive shaft so that all bearings in the said compartments run in a bath of oil. In this respect, it is pointed out that the plate 17 and an associated gasket closes the compartment 12 dust and oil tight. With the looper, loop spreader and needle being arranged to operate in the 75

recess 31 outside of said compartment 12, no dust, lint or foreign particles can enter the compartment 12 to foul the oil therein. Thus such dust and lint will be deposited or will accumulate on the base plate for ready and easy removal.

5 By the arrangement of the parts more directly associated with the rocking of the looper and loop spreader rock shafts, within the chamber 12, greater freedom and safety are provided for the operator's arm beneath the overhanging arm 10 as it removes said parts from beneath the overhanging arm 16. Also this arrangement provides for a better balance of the parts within said compartment for smooth and thus faster operation. Again, a built up crank shaft may be employed with a better bearing arrangement thereof, instead of a forged crank shaft as heretofore necessary. Thus this arrangement may be produced at a lower cost both for manufacture and assembly.

15 20 With the parts running in oil as described, bearing life is greatly increased and this, of course, reduces maintenance costs, servicings and also results in a more quiet operation.

25 While in describing the invention, we have referred in detail to the form, arrangement and construction of the parts as herein shown, the same is to be considered only in the illustrative sense so that we do not wish to be limited thereto except as may be specifically set forth in the appended claims.

30 We claim as our invention—

35 40 45 1. In a sewing machine, the combination of a base plate, a dust-proof casing thereon, a main drive shaft in said casing, a needle bar mounted for reciprocating movement toward and away from said base plate, a rockable looper and a rockable loop spreader arranged outside of the casing for cooperating with the needle in forming stitches, rock shafts for the looper and the loop spreader respectively arranged in the casing, means between said main drive shaft and the rock shafts for actuating the latter, and means in said casing providing lubricated bearings in which said main drive shaft and said rock shafts are journalled.

50 55 60 65 2. In a sewing machine, the combination of a base plate, a dust-proof casing thereon adapted to contain a lubricant, a main drive shaft in said casing, a needle bar mounted for reciprocating movement toward and away from the base plate, a rockable looper and a rockable loop spreader arranged outside the casing for cooperating with the needle in forming stitches, rock shafts for the looper and loop spreader respectively arranged in the casing and driven from said main drive shaft, and means in said casing providing bearings for all of said shafts and which bearings are immersed in said lubricant.

65 70 75 80 3. In a sewing machine, the combination of a base plate, a dust-proof casing thereon, a main drive shaft in said casing, a needle bar mounted for reciprocating movement toward and away from said base plate, a rockable looper and a loop spreader arranged outside of the casing for cooperating with the needle in forming stitches, rock shafts for the looper and loop spreader respectively, arranged in the casing, a driven shaft arranged at an angle to and driven by said main drive shaft, means between said driven shaft and the rock shafts for actuating the latter, and means in said casing providing lubricated bearings for said drive, driven and rock shafts respectively.

75 4. In a sewing machine, the combination of a

base plate, a dust-proof casing thereon adapted to hold a lubricant, a main drive shaft in said casing, a needle bar mounted for reciprocating movement toward and away from the base plate, a looper and a loop spreader arranged outside of the casing for cooperating with the needle in forming stitches, rock shafts for the looper and loop spreader respectively arranged in the casing, a driven shaft arranged at an angle to and driven by said main drive shaft, means between said driven shaft and the rock shafts for actuating the latter, and means in said casing immersed in said lubricant providing bearings for said drive, driven and rock shafts respectively. 5

5 10 15 20 25 30 5. In a sewing machine, the combination of a base plate, a dust-proof casing thereon adapted to hold a lubricant, a main drive shaft in said casing, a needle bar mounted for reciprocating movement toward and away from the base plate, a looper and a loop spreader respectively arranged outside of the casing for cooperating with the needle in forming stitches, rock shafts for the looper and loop spreader respectively arranged in the casing, a driven shaft arranged at an angle to and driven by said main drive shaft, a plurality of crank arms carried by the driven shaft, means between said crank arms and said rock shafts for actuating the latter, and means in said casing immersed in said lubricant providing bearings for said drive, driven and rock shafts respectively.

35 40 45 50 55 60 65 70 75 80 85 90 95 6. In a sewing machine, the combination of a base plate, a dust-proof casing thereon adapted to hold a lubricant, a main drive shaft in said casing, a needle bar mounted for reciprocating movement toward and away from the base plate, a looper and a loop spreader respectively arranged outside of the casing for cooperating with the needle in forming stitches, rock shafts for the looper and loop spreader respectively in the casing, a driven shaft arranged at a right angle to said main drive shaft and driven therefrom, a crank arm on each end of the driven shaft, means between said crank arms and the rock shafts for actuating the latter, and means in said casing immersed in said lubricant and providing bearings for said drive, driven and rock shafts respectively.

90 95 100 105 7. In a sewing machine, the combination of a base plate, a dust-proof casing thereon adapted to hold a lubricant, a main drive shaft in said casing, a hollow arm supported on said base plate, a needle bar having bearing in one end of said arm for a reciprocating movement toward and away from the base plate, a needle bar lever pivotally mounted in said arm and operatively connected at one end to the needle bar, means in the other end of said arm and driven from said main drive shaft and connected to said lever for actuating the latter, mechanism arranged outside of the casing for cooperating with the needle in forming stitches, means in said casing including shafts actuated from said main drive shaft for actuating said mechanism, a pump in said casing driven from said main drive shaft, and means for delivering lubricant from the pump to the bearings for the needle bar and lever respectively and for returning lubricant from said arm back to the casing.

8. In a sewing machine, the combination of a base plate, a dust-proof casing thereon adapted to hold a lubricant, a main drive shaft in said casing, a hollow standard and arm supported on said base plate, a needle bar having bearing in one end of said arm for a reciprocating move- 75

- ment toward and away from the base plate, a needle bar lever pivotally mounted in said arm and operatively connected at one end to the needle bar, means in the hollow standard and driven from said main drive shaft and connected to said lever for rocking the latter, a rockable looper and a rockable loop spreader arranged outside of the casing for cooperating with the needle in forming stitches, rock shafts for 10 said looper and loop spreader respectively, means between said main drive shaft and rock shafts for actuating the latter, bearings in said casing for said shafts and immersed in said lubricant, a pump also in said casing driven from said main 15 drive shaft and immersed in said lubricant, and means for delivering lubricant from said pump to the bearings for the needle bar and lever respectively and for returning lubricant from said arm back to the casing.
- 20 9. In a sewing machine, the combination of a base plate, a dust-proof casing thereon adapted to hold a lubricant, a main drive shaft in said casing, a needle bar mounted for reciprocation toward and away from the base plate, a feed dog arranged outside of said casing for cooperation with said needle, a rock shaft for said feed dog and arranged parallel with said main drive shaft, a bearing for one end of said feed dog rock shaft arranged in said casing, a second bearing for said 25 feed rock shaft arranged outside said casing but having an oil duct communication with the interior thereof, a looper and a loop spreader arranged outside said casing for cooperating with the needle in forming stitches, rock shafts for 30 the looper and loop spreader arranged in the casing, means in said casing between said main drive shaft and first mentioned end of the feed dog rock shaft for actuating the latter, means in said casing between said main drive shaft and the rock shafts for the looper and loop spreader for actuating said rock shafts, and means in said 35 casing providing bearings immersed in said lubricant for the first mentioned end of the feed dog rock shaft, the main drive shaft and the looper and loop spreader rock shafts respectively.
10. In a sewing machine, the combination of a base plate, a main drive shaft journaled thereon, a needle bar mounted for reciprocation toward and away from the base plate, a rockable looper and a rockable loop spreader arranged on the base plate for cooperating with the needle in forming stitches, rock shafts for said looper and loop spreader respectively, a shaft arranged at an angle to and driven from the main drive shaft and means between said driven shaft and said 55 rock shafts for actuating the latter.
11. In a sewing machine, the combination of a base plate, a main drive shaft journaled thereon, a needle bar mounted for reciprocation toward and away from the base plate, a rockable looper and a rockable loop spreader arranged on the base plate for cooperating with the needle in forming stitches, rock shafts for said looper and loop spreader respectively, a crank shaft driven by the crank shaft and means between said crank pins and said rock shafts for actuating the latter.
12. In a sewing machine, the combination of a base plate, a main drive shaft journaled thereon, a needle bar mounted for reciprocation toward and away from the base plate, a rockable looper and a rockable loop spreader arranged on the base plate for cooperating with the needle in forming stitches, rock shafts for said looper and loop spreader respectively, a second shaft ar-

ranged at an angle to the main drive shaft and carrying crank pins, gearing for driving the second shaft from the main drive shaft and means between said crank pins and said rock shafts for actuating the latter.

13. In a sewing machine, the combination of a base plate, a dust-proof casing thereon, a main drive shaft in said casing, a needle bar mounted for reciprocating movement toward and away from the base plate, a plurality of rock shafts 10 arranged with portions inside the casing and with other portions outside the casing, means between said main drive shaft and those portions of said rock shafts inside the casing for actuating said rock shafts, means in said casing providing lubricated bearings in which said main drive shaft and said rock shafts are journaled, and means on said portions of the rock shafts outside the casing for cooperating with the needle in forming stitches. 20

14. In a sewing machine, the combination of a base plate, a dust-proof casing thereon, adapted to contain a lubricant, a main drive shaft in said casing, a needle bar mounted for reciprocating movement toward and away from the base plate, 25 a plurality of rock shafts arranged with portions inside the casing and with other portions outside the casing, means between said main drive shaft and those portions of said rock shafts inside the casing for actuating said rock shafts, 30 means in said casing providing bearings for all of said shafts and which bearings are immersed in said lubricant, and means on said portions of the rock shafts outside the casing for cooperating with the needle in forming stitches. 35

15. In a sewing machine, the combination of a base plate, a dust-proof casing thereon adapted to contain a lubricant, a main drive shaft in said casing, a crank shaft extending transversely of the main shaft and driven therefrom, a rock shaft 40 arranged with one portion inside and a second portion outside the casing, means between the crank shaft and that portion of the rock shaft inside the casing for actuating the rock shaft, means providing a part of a stitch forming mechanism on said second portion of the rock shaft outside the casing, and means in said casing providing bearings for said shafts and which bearings are immersed in said lubricant.

16. In a sewing machine, the combination of a base plate, a casing thereon adapted to hold a lubricant, a main drive shaft journaled in said casing, means on said casing providing an upright hollow standard and overhanging arm communicating with said casing, a needle bar mounted in bearings in said arm for reciprocating movement toward and away from the base plate, a rockable lever pivoted at a point between its ends in said hollow arm and operatively connected at one end to the needle bar, means in the hollow 60 standard and driven from the drive shaft and connected to the other end of said lever for rocking the same, mechanism outside of the casing for cooperating with the needle in forming stitches, means in said casing between said main drive shaft and said mechanism for actuating the latter, a pump in the casing and driven from said main drive shaft and having an inlet arranged below the level of the lubricant contained in said casing, and means extending up through the 70 standard and arm for delivering lubricant to the bearings for the needle bar, the pivot for the lever and the connection between said other end of said lever and the means in the hollow standard, the excess lubricant draining from said hol- 75

low arm and standard back into the casing.

17. In a sewing machine, the combination of a base plate, a casing thereon adapted to hold a lubricant, a main drive shaft journalled in said casing, means on said casing providing an upright hollow standard and overhanging arm communicating with said casing, a needle bar mounted in bearings in said arm for reciprocating movement toward and away from the base plate,
- 10 a rockable lever pivoted at a point between its ends in said hollow arm and operatively connected at one end to the needle bar, means in the hollow standard and driven from said main drive shaft and connected to the other end of said lever for rocking the same, mechanism outside of the casing for cooperating with the needle in forming stitches, means in said casing between said main drive shaft and said mechanism for actuating the latter, a pump in the casing and
- 15 driven from said main drive shaft and having an inlet arranged below the level of the lubricant contained in said casing, a tube leading from said pump to a manifold in said hollow arm, and

tubes leading from said manifold, each to the needle bar, pivot for said lever and the connection between said other end of said lever and the means in the hollow standard.

18. In a sewing machine, the combination with a base plate, an upright wall on said plate providing a casing to hold a lubricant, a part of said wall being formed to provide a recess in said base plate outside said casing, a drive shaft in said casing, a needle bar mounted for reciprocating movement toward and away from the base plate, within the area of the recess, a rockable looper and a rockable loop spreader arrangement in said recess for cooperating with the needle in forming stitches, rock shafts for the looper and loop spreader respectively, journalled in bearings formed in parts of said upright wall, but submerged in the lubricant, and means between said drive shaft and said rock shafts for actuating the latter.
